APPLIQUE FOR AN AQUARIUM

Robert Newsteder, 5 Valley Way,
West Orange, N.J. 07052

Filed Sept. 9, 1968, Ser. No. 13,459

Term of patent 14 years

Int. Cl. D30—01

U.S. Cl. D30—12

FIG. 1

FIG. 2

FIG. 1 is a front elevational view of an applique for an aquarium according to my new design;

FIG. 2 is a fragmentary vertical sectional view substantially on the line 2—2 of FIG. 1.

The broken line showing in FIG. 1 is depicted for illustrative purposes only.

I claim:

The ornamental design for an applique for an aquarium, as shown.
